[57] CLAIM

The ornamental design for a tray for biological samples,
as shown and described.

DESCRIPTION

FIG. 1 is a perspective view of a tray for biological
samples showing my new design;

FIG. 2 is a top plan view thereof;

FIG. 3 is a bottom plan view thereof;

FIG. 4 is a right side elevational view thereof, the left
side elevational view being identical;

FIG. 5 is a front elevational view thereof, the rear ele-
vational view being identical;

FIG. 6 is a perspective view of a second embodiment of
a tray for biological samples showing my new design;

FIG. 7 is a top plan view thereof;

FIG. 8 is a bottom plan view thereof;

FIG. 9 is a right side elevational view thereof, the left
side elevational view being identical; and,

FIG. 10 is a front elevational view thereof, the rear
elevational view being identical.

FIG. 1
